CLAIM

The ornamental design for a furniture set, as shown and described.

DESCRIPTION

FIG. 1 is a perspective view of a furniture set showing my new design, the set comprises one long chair, two identical short chairs, two identical leg rests and a table;

FIG. 2 is a front elevational view of the table of the set, shown separately for completeness of illustration;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a perspective view thereof;

FIG. 9 is a front elevational view of one of the short chairs of the set, shown separately for completeness of illustration;

FIG. 10 is a rear elevational view thereof;

FIG. 11 is a left side view thereof;

FIG. 12 is a right side view thereof;

FIG. 13 is a top plan view thereof;

FIG. 14 is a bottom plan view thereof;

FIG. 15 is a perspective view thereof;

FIG. 16 is a front elevational view of the long chair of the set, shown separately for completeness of illustration;

FIG. 17 is a rear elevational view thereof;

FIG. 18 is a left side view thereof;

FIG. 19 is a right side view thereof;

FIG. 20 is a top plan view thereof;

FIG. 21 is a bottom plan view thereof;

FIG. 22 is a perspective view thereof;

FIG. 23 is a front elevational view of one of the leg rests of the set, shown separately for completeness of illustration;

FIG. 24 is a rear elevational view thereof;

FIG. 25 is a left side view thereof;

FIG. 26 is a right side view thereof;

FIG. 27 is a top plan view thereof;

FIG. 28 is a bottom plan view thereof; and,

FIG. 29 is a perspective view thereof.

The two short chairs are identical to each other, and the two leg rests are identical to each other. For simplicity, only the views of one of the short chairs and the views of one of the leg rests are illustrated.
